DESIGN FOR AN ASH TRAY

Olive Matthews, Memphis, Tenn.

Application October 29, 1941, Serial No. 103,944

Term of patent 7 years

To all whom it may concern:

Be it known that I, Olive Matthews, a citizen of the United States and a resident of Memphis, in the county of Shelby and State of Tennessee, have invented the new, original, and ornamental Design for an Ash Tray, of which the following is a specification, reference being had to the accompanying drawing, forming part thereof, in which:

I claim:

The ornamental design for an ash tray, as shown,

OLIVE MATTHEWS.
